HARRY R. KONIKOFF, OF NEW YORK, N. Y.

ADJUSTABLE DRESS-FORM.

1,313,303.

Specification of Letters Patent.

Patented Aug. 19, 1919.

Application filed May 19, 1915. Serial No. 29,093.

To all whom it may concern:

Be it known that I, HARRY R. KONIKOFF, a citizen of the United States, and a resident of New York, in the borough of Bronx, county of Bronx, and State of New York, have invented certain new and useful Improvements in Adjustable Dress-Forms, of which the following is a specification.

My invention relates to adjustable and collapsible dress forms of the class used by dress-makers, and one of the main objects thereof is to provide a frame for supporting the bust sections which consists of a diaphragm, neck-plate, and connecting rods comprising a unit, said diaphragm being itself supported by the conventional base and telescopic rod, this construction being of great advantage over the hitherto known method of suspending the bust portion and skirt portion from the neck-plate and which, in turn, is mounted on the telescopic rod; in the latter form the bust and skirt portions may sway from side to side and, if the weight of material on one side of the dress form be heavier than on the opposite side, a permanent list results, preventing proper adjustment of the length of a skirt, whereas in my form the entire weight is carried by the diaphragm located within the hip sections and no list of the dress form can occur to prevent proper fitting of the skirt length.

A further object is to provide means for adjustably locking the bust sections together of such form as to be easily operable by persons entirely lacking in mechanical skill, and wherefrom no parts may be detached and possibly lost.

A further object is to provide absolutely independent adjustable locking means for the separate neck sections not dependent upon a threaded knob as in the dress forms known to me; in this old form each neck section has an inwardly directed horizontal arm thereon resting upon the neck-plate, a supplemental plate resting upon all of the arms, and a threaded knob for locking said plates together with the arms therebetween but, as soon as this knob is loosened, all of the neck sections sag outwardly and it is difficult to readjust all of them at one time previous to locking them in desired positions by the said knob; in my form, however, the knob and supplemental plate, if used, may be entirely removed without affecting the neck sections in the least, each neck section being then individually adjustable.

A further object is to provide a simple and positive adjusting device for each hip section whereby it may be vertically adjusted individually, and a still further object is to provide a skirt portion of the utmost simplicity but the adjustable sections of which move freely with the respective hip sections to which they are attached.

My invention is fully described in the following specification, of which the accompanying drawings form a part, in which like characters refer to like parts in each of the views, and in which:

Fig. 1 is a front elevation of a dress form constructed in accordance with my invention, partly broken away and partially in section;

Fig. 2 is an enlarged section taken on the line 2—2 of Fig. 1;

Fig. 3 is an enlarged, fragmentary, view of a locking device which I employ for the several bust sections;

Fig. 4 is a section taken on the line 4—4 of Fig. 3;

Fig. 5 is an enlarged, fragmentary, section taken on the line 5—5 of Fig. 1;

Fig. 6 is a fragmentary detail of the skirt portion;

Fig. 7 is an enlarged section taken on the line 7—7 of Fig. 1;

Fig. 8 is an enlarged section taken on the line 8—8 of Fig. 10;

Fig. 9 is a section taken on the line 9—9 of Fig. 8;

Fig. 10 is a section taken on the line 10—10 of Fig. 1; and

Fig. 11 is a fragmentary view of the inner surface of the bust portion.

In the drawings forming a part of this application I have shown a dress form comprising a bust portion 12, a skirt portion 13 dependent therefrom, a base 14, and a telescopic standard or rod 15 secured to a cross-head 16 of channeled, stamped, sheet metal, which is adapted to be locked within a recess 17 in a diaphragm 18 by means of a set-screw 19, said diaphragm having two vertical rods fixed thereto which are in turn fixed to a neck-plate 20, said rods being designated 21.

The rods 21 pass through suitably spaced holes in the cross-head 16, as shown at 22, Fig. 10, and it will be seen that the standard 15 is maintained in rigid parallelism with respect to the rods 21, although the cross-head 16 may slide along the rods 21

when the set-screw 19 is loosened, to enable the bust portion to move toward the base 14 until the cross-head 16 rests against the under side of the neck-plate 20, said cross-head being imprisoned on the rods 21.

As shown in Fig. 7, the neck-plate 20 has a plurality of guides 23 for radially adjustable arms 24 arranged at quadrant points in the form shown, each of said guides 10 having a spring clip 25 thereover provided with a pin 26 on the under side thereof adapted to enter any one of a plurality of holes 27 in the respective arms 24 to lock the same in desired positions, each of said 15 arms being secured to a neck section 28 of which there are four in the present form. I may, if desired, arrange a supplemental plate 29 over the guides 23 and a knob 30 for holding this plate in position, but these 20 are more for appearances than for any necessity therefor, as the individual arms 24 remain in adjusted positions irrespective of the plate 29 and knob 30.

In the form illustrated, the rear neck 25 sections extend to the waist line of the bust portion, shown in Fig. 11, whereas the front neck sections extend only to the chest line, as shown in Fig. 1, a breast section 31 being suspended from each front neck section by 30 means of a slide-bar 32, said front neck sections being joined by a slide-bar 33, said breast sections by slide-bars 34, and said rear neck and back sections by means of a slide-bar 35.

35 Joined to the back sections 28, by means of slide-bars 36, are rear shoulder sections 37, Fig. 11, extending from the shoulder to the waist line, and joined to the front neck sections are front shoulder sections 38, by 40 means of slide-bars 39, which extend only to the chest line, Fig. 1. Joined to the respective breast sections 31, by means of slide-bars 40, are side sections 41 which are in line with the respective front shoulder 45 sections 38, and may be joined thereto if desired, although not so shown.

Depending from each back section, Fig. 11, and connected therewith by means of a slide-bar 42, is a rear hip section 43; depending from each rear shoulder section 37, by means of a slide-bar 44, is a rear side hip section 45; depending from each side section 41, by means of a slide-bar 46, is a front side hip section 47; and depending 55 from each breast section 31, by means of slide-bars 48, is a front hip section 49, all of these slide-bars being of adjustable form with respect to the corresponding bust sections, in a manner to be later described.

60 A description of one of the slide-bars 34 joining the breast sections 31 will suffice for all of the slide-bars, as they are all alike. The slide-bar 34 is riveted at 50, Fig. 3, to one of the sections and passes through a 65 guide-plate 51 on the other section, a spring

clip 52 being secured to said guide-plate and carrying a pin on its under side adapted to enter any one of a plurality of holes in the slide-bar 34, the pin 53 being shown in Fig. 4, and the holes 54 in Fig. 3, and I 70 may provide a knob or handle 55 for the spring clip 52; when the clip 52 is drawn outwardly to release the pin 53 from the particular hole 54 in which it had been engaged, the slide-bar 34 may be moved to 75 adjust the breast sections toward or from each other, and, when the desired adjustment has been attained, the pin 53 may be entered into the proper hole 54 and the 80 said breast sections are locked in desired relationship. This description applies to all the sections and their connecting slide-bars, and it will thus be seen that any of the bust sections may be quickly and easily adjusted with respect to its connected section, 85 and, there being no detachable parts to the slide-bars and connections, no portions thereof can be lost or mislaid.

By reference to Figs. 1, 8, 9 and 10, it will be seen that I provide a plurality of radially adjustable slide-bars 56, one for each 90 of the hip sections, having a plurality of holes 57 therein adapted for engagement with a pin 58 on a spring clip 59, and guided in guide plates 60 in the manner 95 already described, whereby each of said hip sections may be adjusted radially of the diaphragm 18; these slide-bars 56 actually support the respective hip sections and, thereby, the bust sections over the hip sections, the diaphragm thus sustaining the 100 entire weight of the dress form, by means of the said slide-bars and the connected bars 21 and neck-plate 20.

It will be noted that the hip sections are 105 vertically adjustable with respect to the connected bust sections thereover, and I must, therefore, provide means for adjusting the hip sections vertically with respect to the diaphragm and the slide-bars 56; 110 each of these means consists of a vertical elbow 61, on the respective slide-bar 56, having a plurality of holes 62 therein adapted, each, to receive a headed screw 63 115 slidable in a channeled guide 64 and adapted to be locked with respect to said guide by means of a wing-nut 65; when said nut is loosened, the hip section may be adjusted vertically with respect to the respective slide-bar, after which the wing-nut may be 120 again tightened to lock the parts together.

Riveted to each of the hip sections, at the lower edge thereof, is a guide 66 for a vertical slidable strip 67 in turn riveted to the inner surfaces of upper and lower horizontal band sections 68 and 69, respectively, 125 supplemental vertical strips 70 being riveted to the outer surfaces of said bands and to intermediate band sections 71 and 72, the respective strips 67, and 70, and band sec- 130

tions 68, 69, 71, and 72 collectively forming a skirt section joined to the adjacent skirt section by means of a strap 73 secured to the end of each of the band sections of the 5 outer skirt section and encircling the respective band sections of the inner skirt section, as clearly shown in Fig. 6; this sectional arrangement of the skirt portion of the dress form allows of diametrical adjustment of the skirt portion with the diametral adjustment of the lower part of the bust portion, no attempt being made to provide locks 10 for the skirt sections, as the frictional engagement thereof is sufficient under ordinary conditions, although suitable locking 15 means might be employed.

It will thus be seen that I provide a dress form which possesses great flexibility in adjustment but rigidity when adjusted, where- 20 in adequate adjustable slide-bars are pro- vided and means for locking the same in ad- justed positions, wherein the weight is not suspended from the neck-plate but is carried by the diaphragm, and which is also col- 25 lapsible by telescoping the skirt portion over the bust portion. The skirt portion illus- trated is of the general form shown in Let- ters Patent of the United States, No. 1,122,129, issued to M. A. Konikoff and my- 30 self on the 22nd day of December, 1914, but I may also adapt the form shown and de- scribed in a co-pending application filed May 18, 1915, Ser. No. 28,855, and which 35 consists of telescopic sections whereby the bust portion is only partially inclosed when the dress form is collapsed, for storage or shipment.

While I have shown certain preferred de- 40 tails of construction, I do not seek to con- fine myself thereto, but may make changes thereover, within the scope of the follow- 45 ing claims, without departing from the spirit of my invention or sacrificing its ad- vantages.

Having fully described my invention, what I claim as new, and desire to secure by Letters Patent is:—

1. An adjustable dress form, comprising a base, an adjustable standard, a dia- 50 phragm carried thereby, vertical rods car-

ried by said diaphragm, a neck-plate car- 55 ried by said rods, said diaphragm, neck- plate, and rods being immovable with re- spect to each other, a bust portion carried by said diaphragm composed of a plurality 60 of separable upper bust sections and lower hip sections and means for locking the same in desired relationship, and a skirt portion adjustable with said bust portion and adapt- ed to be telescoped thereover.

2. In a device of the class described, a neck-plate, a bust composed of a plurality of sections and means for locking the same in desired relationship with each other, a horizontal arm on one of said sections ex- 65 tended inwardly over said neck-plate, a guide on said neck-plate for said arm, said arm being provided with a plurality of holes therein, and a spring clip on said neck- plate having a pin adapted to enter one of 70 said holes to lock said section in desired relationship with respect to said neck-plate.

3. An adjustable dress form comprising a bust portion consisting of a dia- 75 phragm, a neck-plate, a pair of parallel rods vertically disposed within said bust portion and immovably connected to the diaphragm and neck plate respectively, a plurality of separable sections, means for adjustably connecting the said sections to 80 the diaphragm and neck-plate respectively and with each other; a skirt portion ad- justably connected to said bust portion at or near its lower end, and a standard having an adjustable connection with the vertical 85 rods of the bust portion.

4. In an adjustable dress form a verti- 90 cally adjustable standard and a support thereupon, angle brackets adjustably se- cured to said support, a section adjustably secured to each of said angle brackets and means whereby said sections may be moved radially and vertically upon said brackets.

In testimony whereof I have signed my name to this specification in the presence of 95 two subscribing witnesses.

HARRY R. KONIKOFF.
